W. A. MORRIS

CARTON

Filed Nov. 2, 1922

INVENTOR:

Warren A. Morris

BY

Allen & Allen
ATTORNEYS.

UNITED STATES PATENT OFFICE.

WARREN A. MORRIS, OF CINCINNATI, OHIO, ASSIGNOR TO THE RICHARDSON COMPANY, OF LOCKLAND, OHIO, A CORPORATION OF OHIO.

CARTON.

Application filed November 2, 1922. Serial No. 598,627.

To all whom it may concern:

Be it known that I, WARREN A. MORRIS, a citizen of the United States, and a resident of Cincinnati, in the county of Hamilton and State of Ohio, have invented certain new and useful Improvements in Cartons, of which the following is a full, clear, and exact description, reference being had to the accompanying drawings, forming part 10 of this specification.

My invention relates to cartons as employed with material which is to be poured therefrom in small quantities. Of such a 15 type are soap powder or soap chip cartons, salt, and soda cartons, and cartons for many other materials.

It is the object of my invention to so form a carton or container that the user can, by a simple punching out of certain perforations or weakened portions, form of the 20 structure left after the punching, a spout for the container that communicates with the contents therein.

It is also the object of my invention to 25 form such a container without use of extra material and to provide a spout which will be effective in directing the contents of the box where the user desires.

I am aware of attachments being mounted 30 on cartons which may be employed as spouts, but my device is to be shipped flat, and filled and closed or sealed at the factory, as is any usual carton, thereby providing for much economy and avoiding the 35 changing of packaging methods over usual factory practice.

These various objects I accomplish by 40 that certain construction and arrangement of parts to be hereinafter more specifically pointed out and claimed.

In the drawings,

Figure 1 is a perspective view of the carton entirely closed.

Figure 2 is a perspective view showing 45 the spout in use.

Figure 3 is a plan view of the box blank cut and creased.

Referring first to the blank, which in this 50 case is of a standard soap chip or soap powder package, it will be noted that there are the large sections 1, 1, to form the wide sides of the box, and the narrow sections 2, 2, to form the narrow sides of the box, with an added glue flap 3.

The bottom end closing flaps comprise 55 two wide flaps 4, 4, and two narrow flaps, 5, 5.

The top end closing flaps comprise the two wide flaps 6, 6, and the one standard top flap 7. The other top flap is cut with a 60 main body portion 8 and two side portions 9, 9, which are curved and cut away from what would ordinarily be a portion of the wide flaps 6, 6.

The lines of fold or creases between the 65 special top flap, as indicated at 10, 10, leave a rectangular body 8 and the two wing or side portions 9, 9, having the special curved formation shown.

The two wide flaps 6, 6, are fractured or 70 perforated along the curved lines 11, 11, which curved lines will lie directly over the curved end of the flap portion 8 when the box is set up.

In setting up the box, the various 75 portions are folded to make a rectangular package in the usual manner, and the flap portion 3 is tucked inside of the end portion 2 and cemented. The bottom of the box is made in the usual manner with the wide 80 flaps 4 on the outside and the narrow ones folded in, and the assembly cemented.

In closing the top of the box, the wings 9 are bent at right angles to the flap portion 8 and then the flap folded inwardly to rest 85 on the contents of the package with the wings extending down into the contents. The other narrow top flap is folded in, and the two wide flaps folded over, and the wide flaps cemented together and to the narrow 90 flaps 7 and 8. This results as will be noted in reinforcing the base of the spout formed by part 8.

This leaves a package with the fractured 95 line 11 of the two wide flaps coinciding, so that the user can punch these portions out, leaving the flap portion 8 exposed.

This flap portion 8 is then pulled out, together with the parts of 6 that have been cemented to the part 8, as noted, resulting in 100 a pouring spout, as indicated in Figure 2, with the wings 9 serving as the sides of the spout. The material of the box at the fold or crease line of the flap 8 serves 105 as a hinge therefor, so that it can be bent back onto the top of the box when same is not in use.

It will be noted that the ends of the flaps

9 are cut at such an angle and at such a position, that they will engage the edges of the opening left in punching out flaps 6 and releasing flap 8. This supports the spout and 5 prevents excessive strain sufficient to destroy the tenacity of the paper at the hinge.

In cutting the flaps 9 I prefer that a slight nick be formed in the knife, so that the flap 9 at the side toward the glue flap 3 is left 10 united with flap 6 at 12. In preparing the box for shipment, the flap 9 that is united will fold over with the members 1 and 6 so that the other side flap 2 may fold down and be glued to flap 3, making a flat body to 15 the box for shipment. In charging the package, the body will be opened, the bottom end flaps closed, and the goods inserted. In closing the top of the box, the connection of the one flap is first fractured with very 20 slight pressure.

I find this arrangement to be quite simple to manufacture, and easy to put into use, and that it does not appreciably interfere with the factory operations of filling the carton. 25 In cost, it is not enough different from the cost of the usual rectangular carton to be a disadvantage.

Having thus described my invention, what I claim as new and desire to secure by Letters Patent, is:—

1. In a carton, the combination with a structure formed from a single blank, of closing tabs folded from said blank, one of said tabs folded in from one of the narrow sides of the carton at the top end thereof, said tab having lateral extensions adapted when the tab is turned out to form the sides of a spout, of which spout the tab forms the base, and the tabs at the wide

sides formed with fracture lines, whereby 40 they may be punched out to leave the selected tab free for bending away from the top of the box.

2. A carton blank for the purpose described, comprising sections scored to form 45 the wide and narrow sides of a carton, separated flaps to fold in over the carton structure, with the said flaps at one end of the blank being formed with a central flap, having a body with an end and sides bounded by 50 lines of the narrow side section from which it extends, and lateral extensions connected to the body of the flap and severed from the blank sections forming the box sides, and with the two flaps extending from the wide 55 side sections formed with broken lines of the same shape as the end of said central flap, when folded in, which will form a line of breakage coincident with the end of the 60 said central flap.

3. In a carton, the combination with a structure formed from a single blank, of closing tabs folded from said blank, one of said tabs folded in from one of the narrow 65 sides of the carton at the top end thereof, said tab having lateral extensions adapted when the tab is turned out to form the sides of a spout, of which spout the tab forms the base, and the tabs at the wide sides formed with fracture lines, whereby 70 they may be punched out to leave the selected tab free for bending away from the top of the box, one of the lateral extensions at least being left with a fracturable engagement with the 75 carton blank, which is broken when the carton is filled.

WARREN A. MORRIS.
